(57) **CLAIM**

The ornamental design for a surgical apparatus, as shown and described.

DESCRIPTION

FIG. 1 is a perspective view of a surgical apparatus showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is another perspective view thereof;

FIG. 9 is yet another perspective view thereof;

FIG. 10 is still yet another perspective view thereof; and,

FIG. 11 is still yet another perspective view thereof.

The surgical apparatus illustrated in FIGS. 1-11 may be a surgical navigation apparatus such as, for example, a lung navigation apparatus.
